(57) **CLAIM**

The ornamental design for an exhaust pipe cover for water heater, as shown and described.

DESCRIPTION

FIG. 1 is a front, plan and left side perspective view of an exhaust pipe cover for a water heater showing my new design; FIG. 2 is another front, plan and left side perspective view thereof;

FIG. 3 is a rear, bottom and right side perspective view thereof;

FIG. 4 is another rear, bottom and right side perspective view thereof;

FIG. 5 is an exploded perspective view thereof;

FIG. 6 is a front view thereof, the rear view being the same;

FIG. 7 is a top plan view thereof;

FIG. 8 is a bottom plan view thereof;

FIG. 9 is a right side view, the left side view being the same;

FIG. 10 is a sectional view taken along cut line 10-10 of FIG. 6;

FIG. 11 is a sectional view taken along cut line 11-11 of FIG. 6; and,

FIG. 12 is a reference view showing an in-use state thereof. Throughout the drawings, the broken lines depict environmental structure that forms no part of the claimed design.
